(57) **CLAIM**

The ornamental design for a stopping track component, as shown and described.

DESCRIPTION

FIG. 1 is a front-top perspective view showing a stopping track component;

FIG. 2 is a rear-top perspective view of FIG. 1;

FIG. 3 is a bottom-front perspective view of FIG. 1;

FIG. 4 is a bottom-rear perspective view of FIG. 1;

FIG. 5 is a top side view of FIG. 1;

FIG. 6 is a bottom side view of FIG. 1;

FIG. 7 is a front side view of FIG. 1;

FIG. 8 is a rear side view of FIG. 1;

FIG. 9 is a left side view of FIGS. 1; and,

FIG. 10 is a right side view of FIG. 1.
